UNITED STATES PATENT OFFICE.

JOHN THOMPSON, OF BUCYRUS, OHIO, ASSIGNOR TO THE BUCYRUS FOUNDRY AND MANUFACTURING COMPANY, OF SAME PLACE.

TRAVELING CRANE AND DERRICK.

SPECIFICATION forming part of Letters Patent No. 272,987, dated February 27, 1883.

Application filed January 17, 1883. (No model.)

To all whom it may concern:

Be it known that I, JOHN THOMPSON, of Bucyrus, in the county of Crawford and State of Ohio, have invented certain Improvements in Traveling Cranes; and I hereby declare the following to be a full, clear, and exact description of the same, reference being had to the accompanying drawings, making part of this specification, in which—

10 Figure 1 illustrates a section of a movable platform, car, or carriage, which carries the crane and the mast of the crane, with my improvements. Fig. 2 is a plan view of the same. Fig. 3 is a detail elevation of the jack-arm, partially in section.

15 My invention relates to traveling cranes or derricks, which are used for a variety of well-known purposes, and has for its object to increase the breadth or length of the bearing of 20 the support of the mast of the crane or derrick, so as to avoid the danger of tipping the support or bearing and throwing the mast out of a vertical line.

25 My invention consists in a removable jack-arm secured to the platform or bearing of the traveling crane, and adapted to have its outer end rest upon the ground at some desired point outside of the wheels or other supports of the platform.

30 In order that those skilled in the art may make and use my invention, I will proceed to describe the manner in which I have carried it out.

35 In the said drawings, A is the movable platform or car supporting the mast B of the traveling crane or derrick. In the drawings the boom and working parts thereof are not shown, as they are not material to my present invention.

40 On the top of the platform, in the rear of the mast, is bolted transversely a channel-bar, c, and at its end, and between ribs a a, is bolted a casting, D, for a purpose hereinafter set forth.

45 The casting D consists of a base-plate, b, an upright plate or projection, d, having two ears, e e, projecting outwardly at right angles to its face, and two ears, i i, projecting inwardly at an angle toward the mast, and having their lower edges integral with base-plate b. Pivoted to the mast, near its upper end, at k, is one end of a brace, E, which extends to casting D, and is bolted in the ears i i, as shown.

Beneath the platform, at its edge, and a short distance within the edge, are two strengthen-

ing-pieces, preferably of channel-iron, F G, 55 (shown in dotted lines.) Bolted at its ends to F and G is a short channel-iron piece, H, against each side of which rests a leg or bar, I I, forming the projecting jack-arm. These bars I I have their inner ends resting between the 60 flanges of channel-piece G, and are held to piece H by bolt p, and have securely bolted through their outer ends a head, J, which is tapped to receive a jack-screw, L, and is provided with ears n n on the side next to the 65 car. A diagonal brace, M, has one end bolted in the ears n n and the other end bolted in the ears i i. When a load is to be lifted, or other heavy work performed, the screw L is run down until its lower end has a firm bearing on the ground and the tipping of the platform is prevented.

70 By the use of this jack-arm I am enabled to cut off or round off the platform at its ends, and thereby work may be done close to and at 75 right angles with the car, as shown at t t, Fig. 2. When the platform or car is to be transported, bolts p and q are removed, and the entire jack-arm is removed and stowed upon the car. Any number of these jack-arms may be 80 applied to one car without departing from the spirit of my invention, and if found desirable the brace M may be dispensed with, as it is only an additional safeguard to bars I I.

Having thus described my invention, what I 85 claim as new and desire to secure by Letters Patent, is—

1. In a traveling crane or derrick, the supporting platform A, in combination with a jack-arm adapted to increase the length or 90 breadth of the bearing of said platform, substantially as set forth.

2. The jack-arm consisting of the bars I I, head J, screw L, casting D, constructed as described, and channel-pieces G and H, all constructed, arranged, and operated as described.

3. The jack-arm constructed substantially as described, in combination with the brace E, pivoted to the mast at k and to ears i i, substantially as specified.

4. In combination with a crane or derrick and a jack-arm adapted to enlarge the bearings of a traveling crane, the platform A, having its corners cut away, for the purpose set forth.

JOHN THOMPSON.
